UNITED STATES PATENT OFFICE.

WILHELM ROHN, OF HANAU, GERMANY.

INDUCTION FURNACE.

Application filed December 21, 1920. Serial No. 432,308.

To all whom it may concern:

Be it known that I, Dr. WILHELM ROHN, chemist, a citizen of Germany, and resident of Hanau, Germany, have invented new and useful Improvements in Induction Furnaces, (for which I have filed applications in Germany, May 19, 1920; Sweden, July 30, 1920; Norway, September 11, 1920; Czecho-Slovakia, July 24, 1920), of which the following is a specification.

Electric induction smelting furnaces described in patents and scientific publications as well as those used in the industry, make use of the discovery that by passing a sufficiently strong electric current, metals can be made red hot and even heated to the point of melting, so that in that way a heating sufficient for carrying out metallurgical processes, can be obtained. In order to melt in that way any considerable quantities of metal and to obtain favourable conditions from the point of view of heat utilization, the material to be melted used to be given a comparatively large cross-section, and therefore it was necessary to use extraordinarily great strength of current at low voltage. It has been therefore attempted to use constructions in which the material to be melted was introduced into a channel which was closed in itself, and the said channel was arranged direct as a secondary coil of a transformer, that is to say the primary current flowed round an iron core, which passed through the center of the melting channel while the secondary current is generated in this channel.

Although such furnaces have been extensively used in practice, they have the following important disadvantages:

40 A. The efficiency factor $\cos \phi$ is very unfavourable. The reason of this must be looked for in various circumstances, that is, (1) In the fact that the distances from the melting channel to the primary coil and to the transformer core become unfavourably great. This results in the dispersion of the transformer being great, and in the coupling between the primary coil and the secondary coil (i. e. the melting channel) being very loose. In such a transformer, even with the secondary coil short-circuited, the inductance of the primary coil is not small enough, and consequently there remains a large wattless load. As however, the machine installations have to be dimensioned for available effect plus wattless effect, the working

of such a furnace requires a current-generating installation two to three times larger than would be required for the available effect alone.

(2) In the usual constructions the transformer cores and the yokes connecting the same, are unfavorably arranged and too large. In that way the path of the lines of force in the transformer iron becomes comparatively too long which also results in an increase of dispersion and of losses through hysteresis.

B. The screening against the inductive action outwards of the surface of the transformer core is insufficient. In the usual constructions the primary coil is screened outwards only in a very inadequate manner so that in all metal parts surrounding the furnace (more particularly in the parts of the furnace casing or jacket) are induced considerable eddy currents which lead to inconvenient heating and losses of energy.

C. The rolling motion of the metal bath is very considerable and disturbing. Owing to the usual arrangements of the primary coil and the melting channel relatively to each other, the bath surface takes up an oblique position in the melting channel, and the material to be melted makes rolling movements which lead to a destruction of the channel walls.

The above mentioned disadvantages are partly avoided, and partly limited to a considerable extent, by the construction of the furnace according to the present invention.

The furnace is diagrammatically shown in the accompanying drawing.

Figure 1 is a vertical section through the furnace,

Figure 2 is a horizontal section,

Figure 3 shows a horizontal section through another construction of the transformer iron.

A is the melting channel, for instance a circular one. It is closely surrounded on all sides by the primary winding B. The primary winding B is in its turn surrounded by the transformer iron C. The transformer iron is constituted by ring shaped (circular, square or the like) sheet metal plates which surround the primary winding and are arranged in a fanlike manner. The body of the transformer iron may be assumed in a way to have been produced by a suitably shaped ring of transformer plate, the plane of which passes through the axis of sym-

metry of the circular melting channel, being rotated around the said axis. In that way a transformer iron will be produced constituted by a closed annular tube. It is immaterial whether, in accordance with the plan in Fig. 2, the single plate-rings forming the yoke, are all exactly radial, squared out only at the points of the charging and tapping holes, or whether they are combined together to form single sub-units in accordance with Fig. 3. The intermediate space between the melting channel and the primary winding is filled in a known manner with refractory material.

In the construction described, the whole of the heat radiated by, and carried away from, the metal bath, after passing through the refractory material, strikes the primary winding. The latter must be therefore sufficiently cooled. This may be done for instance by making the primary winding not of solid round copper but of a tube (owing to which the eddy currents produced in the same, are at the same time considerably reduced) and by cooling the said tube by passing through it cooling water, re-cooled oil or cooling air. In that way the winding itself is maintained cool, and at the same time the transformer iron and the furnace jacket are protected from heating.

In such a furnace construction the described disadvantages of the usual and well known constructions are reduced or avoided owing to the fact

(a) That the primary winding B is constituted by water cooled tubes. This makes it possible, considerably to reduce the distance of the winding from the metal bath.

(b) That the transformer iron surrounds the metal bath along the shortest possible path. In that way the path of the magnetic lines of force is considerably shortened.

Both arrangements are eminently adapted to limit the disadvantage set forth under A (1) and (2) and thereby to improve the $\cos \varphi$.

Moreover, owing to the new arrangement, the known inductive action which in the usual constructions is exercised on the whole surrounding of the melting furnace (disadvantage B) can be practically eliminated owing to the transformer iron surrounding

on all sides the primary and the secondary coil.

In that way it is possible to obtain entirely new working conditions for such furnaces and to make use of new melting processes. By eliminating the inductive action on the fittings or on the constructive enclosure of the furnace, as well as on all the metal parts surrounding it, it becomes possible for instance to place such a furnace with its fittings into a practically gas-tight chamber. The interior of the said chamber can then be filled with any desired gases, and the melting and casting processes carried out under any desired adjustable excess of pressure or depression or in a vacuum and at any desired temperatures and finally can be carried on for any desired length of time.

Finally, the new arrangement makes it possible to eliminate completely the known injurious rolling movements of the metal bath (disadvantage C) owing to the primary coil surrounding the melting channel uniformly on all sides.

Claims:

1. An induction furnace consisting of an annular melting-channel which is surrounded on all sides also above as well as below the channel by the primary coil and both the melting channel and the primary coil are surrounded on all sides by annular shaped transformer iron.

2. An induction furnace as set forth in claim 1 wherein the primary coil consists of tubes which may be cooled by suitable liquids or gases both of which later can be cooled to any desired extent outside the furnace.

3. An induction furnace as set forth in claim 1 wherein the primary coil consists of tubes forming in their totality a kind of an annular tube enclosing the melting channel, and protecting the radially disposed cores of the transformer iron against heating, said tubes being cooled by a suitable cooling agent introduced therethrough from a point outside the furnace.

In testimony, that I claim the foregoing as my invention I have signed my name this 20 day of February 1922.

DR. WILHELM ROHN.
